A. G. McKee,

O. Meekel,
his Attorney

UNITED STATES PATENT OFFICE.

ARTHUR G. MCKEE, OF CLEVELAND, OHIO.

COKE-SCREEN.

1,275,713.

Specification of Letters Patent. Patented Aug. 13, 1918.

Application filed June 16, 1916. Serial No. 104,110.

To all whom it may concern:

Be it known that I, ARTHUR G. MCKEE, a citizen of the United States, resident of Cleveland, county of Cuyahoga, and State 5 of Ohio, have invented a new and useful Improvement in Coke-Screens, of which the following is a specification, the principle of the invention being herein explained and the best mode in which I have contemplated applying that principle, so as to distinguish it 10 from other inventions.

My invention relates to devices for screening coke or the like and especially to that type of coke screens known in the art as 15 "cascade" screens.

The object of the invention is to provide a screen of the above-described character which will be economical of construction and efficient in its operation.

20 A specific object is to so arrange the parts that clogging will be minimized and the material thus efficiently screened; so that a maximum effective screening area may be obtained for a given area of screen; and so 25 that they will permit the screen bars to be readily and quickly removed, whereby the device may be used for screening the coke used for charging blast furnaces, it being understood that in blast furnace practice, the furnace must operate continuously and hence no material interruption in the 30 screening operation is permitted.

The said invention consists of means hereinafter fully described and particularly set 35 forth in the claims.

The annexed drawing and the following description set forth in detail certain means embodying my invention, the disclosed means, however, constituting but one of 40 various mechanical forms in which the principle of the invention may be applied.

In said annexed drawing:—

Figure 1 represents a vertical section of a fragmentary portion of a coke bin to 45 which my improved screen has been applied.

Fig. 2 represents a plan of a fragmentary portion of the screen.

Fig. 3 represents a vertical section of a fragmentary portion of the screening bar support showing one of the bars in side elevation thereon, and in full.

Fig. 4 represents a plan of one of said bars looking in the direction of the arrow *a* in Fig. 3.

55 Fig. 5 represents an end view of one of

said bars looking in the direction of the arrow *b* in Fig. 3.

In the illustrated embodiment of my invention, the latter is applied to a coke bin of any desired construction, provided with 60 an inclined bottom 1, a front wall 2 provided with an opening 3 and side walls 4, as will be understood. The usual wearing plate 5 is provided immediately above the upper end of the screen, and side-members 65 6 are suitably secured laterally of the opening 3 and inclose laterally that portion of the screen projecting from the bin.

Having their upper ends suitably secured to the lower end of the bars 1 are two lateral 70 side bars 7 forming the side supporting members for the screen, these bars inclining downwardly at the required angle and having their lower ends supported by means of a suitable member 8. A suitable gate 9 75 is provided for controlling the discharge of the coke from the bin, which is operated by any suitable or desired means.

Extending transversely between the side bars 7 and secured to the inner surface of 80 the latter by means of suitable rivets 10, is a plurality of supporting bars 11 made of flat steel having one comparatively small dimension, as shown, this dimension being horizontal, the ends of these bars being bent 85 at right angles and the bent portions being secured, as shown, by the said rivets. The upper surfaces of these bars therefore, it will be noted, are located in different horizontal planes. Supported by each two adjacent bars 11 is a series of screen bars 12. The upper end of each such bar is formed 90 with a boss 13 having a vertical rectangular section and the lower surface of this boss is intersected by a slot 14 engaging the upper portion of the supporting bar 11, as shown in Fig. 3. The main or body portion of the bar extends downwardly and has its lower portion resting freely upon the top of the next lower bar 11, the upper surface of the screen bar being inclined as shown. The bars of any given series hence have their lower ends lying laterally adjacent to the upper ends of the bars of the next lower series, so that the bars of any one 105 series are staggered laterally with reference to the bars of an adjacent series, as shown in Fig. 2. The lower end of each bar is made of greater depth than the upper, as shown, so that the upper surfaces of each series 110

lie in parallel planes of less inclination than the inclination of the screen as a whole, thus imparting the "cascade" character to the latter. The lower end-surface 15 of each 5 bar forms an acute angle with the direction of inclination, as shown, and the extreme lower ends of the bars of the one series, lie between the bosses of the adjacent bars of the next lower series, as shown in Fig. 2.

10 The opposite sides of each bar lie in planes which converge so as to intersect in a line forming an acute angle with the plane of inclination of the screen so that these sides may be said to converge downwardly in the direction of inclination and also converge downwardly in a direction at right angles to said direction of inclination, as shown in Figs. 4 and 5. This construction, therefore, produces an arrangement of adjacent screen 15 bars in each series of bars in which the proximate surfaces of such adjacent bars may be said to diverge from each other downwardly in the direction of inclination and to diverge from each other in a direction at right angles thereto.

20

The series of bars begin immediately below the lower end of the wearing plate and a sufficient number of series are provided to produce the necessary screen surface.

25 From the above-described construction, it will be seen that the bars rest loosely upon their supports and may be lifted readily from the latter in an upward direction for the purpose of removal and replacement.

30 At the same time, however, when they are in position, they are securely held against displacement in a downward direction or in the direction of movement of the coke over same as well as held against lateral displacement. This removal may be effected, 35 as will be readily understood, in a very small space of time, so that a defective bar or bars may be removed and replaced by new ones, without materially interrupting the 40 screening operation and hence without any material interruption of the charging operation.

45 By causing the proximate surfaces of the bars to diverge in the direction of inclination, pieces of coke which would otherwise tend to clog and stick in the spaces between the bars, would upon a slight movement downwardly, reach a point in which such space has a greater lateral dimension and 50 would be released and passed through the bars. By also having these proximate surfaces diverge in the direction at right angles to the direction of inclination, this same tendency to free pieces of coke tending to 55 clog is present for the same reason, namely, as these pieces move downwardly, they 60 reach positions in which the lateral dimension of the space increases.

65 By causing the lower end surfaces of the bars to form an acute angle with the plane

of inclination, it will be seen that the coke in passing from one step of the cascade to the next, will travel over a maximum of the effective screening surface of the series of bars. The effective screening surface of 70 any given series of bars is all of that part of the space between the bars which is not vertically above the bars of the next lower series, or not occupied by the lower ends of the bars in the next higher series. For instance, the effective part of the spaces of the series of which the fully shown bar in Fig. 3 is a member, is that part included between the planes indicated by dotted lines $x-x$ and $y-y$. As much of the remaining surface, therefore, as it is possible to use, should be used. Were the lower end of the bar of the form heretofore used and shown by the straight dotted lines in connection with the fragmentary portion of the upper bar shown in Fig. 3, it will be seen that the coke would cascade and strike at a point z , thus rendering ineffective all that portion of the screen spaces above the point z and up to the plane $y-y$. By giving this lower end the inclined form shown, it will be seen that the coke, instead of falling as just described, will describe the curve indicated by the dotted line z' , striking a point z'' considerably above, thus making effective all that 85 space between the planes $z'''-z'''$ and $y-y$ which before was not utilized.

90 The effective screening area, it will thus be seen, is increased as compared with such previous construction.

95 The acute angle imparted to the lower end surface of the bars is made of such a degree as will cause the coke to strike as high up as possible upon any given series of bars, and will hence be dependent upon the 100 velocity of travel of the coke over the screen.

105 It will be understood that while the transverse supporting bars are shown as having their major cross-sectional dimension vertical, they may be so placed as to 110 incline this dimension more or less so long as such inclination is of a degree which will permit the screen bars during the operation to be securely retained by means of the slots or hooks formed in their upper ends.

115 It will also be readily understood by those skilled in the art that the slot may be placed at the bottom of each screen bar and the upper end merely rest upon the upper of the two supporting bars, and that the same 120 result will thereby be obtained as in the described construction, but perhaps by less desirable means.

Having fully described my invention, what I claim and desire to secure by Letters 125 Patent is:—

1. In a cascade screen for coke or the like, the combination of a frame; a series of cross-bars secured to the frame; and a plurality of staggered series of screen-bars loosely 130

mounted on the cross-bars, the construction being such that each screen-bar is provided with a clear path for its removal.

2. In a screen for coke or the like, the combination of a frame; a series of cross-bars secured to the frame and arranged to occupy successively lower levels; and a plurality of series of screen bars loosely mounted on the cross-bars, the same cross-bar supporting the lower ends of one series of screen-bars and the upper ends of the next lower series of screen-bars.

3. In a screen for coke or the like the combination with a support comprising in its structure a plurality of transverse parallel supporting bars having their upper surfaces in different and succeeding horizontal planes; of a plurality of series of screen bars, each series comprising a plurality of downwardly extending and laterally adjacent bars, each of the latter having its upper end engaging one of said supporting bars so as to be upwardly removable therefrom but secured against displacement in the direction of inclination of the screen and its lower end loosely resting upon the next lower supporting bar, the bars of any given series being laterally staggered with reference to the bars of an adjacent series, the construction being such that each screen-bar is provided with a clear path for its removal.

4. In a screen for coke or the like, the combination with transverse supporting bars arranged to occupy successively lower levels; of a plurality of series of screen-bars, each bar being hooked at one end over an upper supporting bar and resting at the other end upon a lower supporting bar, the same bar supporting the lower ends of one series of screen-bars and the upper ends of the next lower series of screen-bars.

5. In a screen for coke or the like, the combination with a plurality of longitudi-

nally extending side bars, and a plurality of transverse supporting bars formed with angularly bent ends, said ends being secured to side bars; of a plurality of staggered series of spaced screen-bars loosely mounted upon said supporting bars, the construction being such that each screen-bar is provided with a clear path for its removal.

6. In a cascade screen for coke or the like, the combination with a plurality of transverse supporting bars placed so as to occupy successive lower levels; of successive series of staggered, overlapping screen bars, each of which has one end provided with a notch intersecting its bottom surface and removably engaging one of said cross-bars, the opposite end resting upon an adjacent cross-bar, the construction being such that each screen-bar is provided with a clear path for its removal, the same transverse bar supporting the lower ends of one series of screen-bars and the upper ends of the next lower series of screen-bars.

7. In a cascade screen, the combination with a suitable support including longitudinally disposed members and transversely disposed members supported thereby and occupying successively lower levels; of a plurality of series of screen-bars each removably engaging the tops of said transverse members at their upper ends, whereby they are held against longitudinal displacement, but removable in an upward direction, their lower ends resting loosely upon said transverse members, the lower ends of said screen-bars being staggered with reference to the upper ends of the next lower series, and the same transverse supporting element being engaged by the upper ends of one series of screen-bars and supporting the lower ends of the next upper series.

Signed by me, this 1st day of June, 1916. 85
ARTHUR G. MCKEE.
